S. H. BARTTER

MEANS OR DEVICE FOR THE RETENTION OF BEDCLOTHES

Filed Nov. 17, 1926

Patented May 3, 1927.

1,627,008

UNITED STATES PATENT OFFICE.

STEPHEN HENRY BARTTER, OF KINGSTON-ON-THAMES, ENGLAND.

MEANS OR DEVICE FOR THE RETENTION OF BEDCLOTHES.

Application filed November 17, 1926, Serial No. 148,861, and in Great Britain August 14, 1926.

My invention relates to an improved means or device which, while allowing for freedom of movement on the part of the sleeper, will yieldingly retain the clothes in proper position over the bed, will prevent said clothes from becoming disarranged or untucked to the discomfort of the sleeper.

Broadly, the means or device comprises a pair of oppositely disposed, or it may be two or more pairs, of clip or retaining members each constituted by a metal plate adapted to be affixed detachably to the angled side of a bed rail in a vertical position, a spring-controlled slide bar carried by and vertically and slidably mounted in front of said plate, a clip consisting of two rubber-faced jaw members hingedly connected together and fixedly connected by one member to said slide bar, and means pivotally carried by the fixed clip member to effect the instantaneous grip of the clip members on to the bedclothes, or the release thereof.

In order that the said invention may be the more readily understood, reference is to be had to the following description and accompanying sheet of drawings, wherein:—

Figure 1 is a vertical sectional view of the means or device shown attached to a bed rail and wire mattress, the gripping means being shown in full lines in the locked position, and in dot-and-dash lines in open position.

Figure 2 is a front view of said means or device.

Figure 3 is a fragmentary view illustrative of a modified means of attaching the device to the side rail of the bedstead.

Figure 4 is a fragmentary view illustrative of the handling and adjusting means hereinafter referred to.

Like letters of reference indicate corresponding parts in the several figures.

In carrying out the invention and referring first to Figures 1 and 2 of the drawings, the means or device comprises a metal plate *a* of convenient length, width and thickness, provided with a convenient number of suitably spaced apart slots *b* therein for the reception of a buckled strap *c* whereby to detachably fasten said plate *a* to the bed rail *d* of an iron bedstead in a higher or lower position in relation to the frame *e* of the wire mattress *f* into which is hooked the hook *g* of a strap *h* which is affixed to the upper end of the attachment plate *a* and is carried down in front of and

to the bottom of said attachment plate *a* and affixed thereto, said strap *h* being provided with a socket *i*, or it may be sockets, positioned below the upper end of the plate *a* aforesaid.

Freely and slidably mounted in and through the socket or sockets *i* is the inner arm of an inverted U-shaped slide bar *j* which extends a convenient distance down 65 in front of that portion of the strap *h* which is in front of the plate *a* and at its lower end is connected to a cylindrical spring *k* which by its lower end is conveniently anchored to the lower end of the attachment 70 plate *a*, whilst to the front and downwardly depending arm of said slide bar *j* there is fixedly secured the inner member *m* of the clip.

To the lower end of said member *m*, which 75 member *m* is downwardly and outwardly inclined, there is hingedly connected at *n* the lower end of a springy curved outer member *o* of the clip, said clip members *m* and *o* being at their upper ends each fitted with 80 a serrated-faced rubber pad *p*.

To the lower end of the front arm of the slide bar *j* there is hingedly connected the ends of the arms of a bridge-piece *q* which is fitted with a thumb-screw *r* adapted to be 85 screwed in or out so as to bear, more or less, on the arcuate front face of the outer clip member *o* aforesaid.

In use, the bridge-piece *q* is pushed downwards to release pressure on the front member *o* of the clip, with the result that said bridge-piece *q* and front member *o* instantly fall by gravity into the position shown in dot-and-dash lines in Figure 1, leaving the back member *m* of the clip clear. The bedclothes *s* are then pulled down to in front of and below the rubber pad *p* of the inner clip member *m*, and the bridge-piece *q* is then pulled upwards, and with it the front clip member *o* to engage the rubber pad *p* 100 of said member *m* with the bedclothes *s* aforesaid, as shown in full lines in Figure 1 of the drawings.

In the above manner are the bedclothes *s* gripped and retained in position over the 105 bed with a give-and-take vertical up and down and sideways movement of the slide bar *j* provided for by the spring-control *k* and the socket *i* of the strap *h*.

If desired, and to assist in the quick release or opening of the clip, the hinged connection thereof may be spring-controlled.

The radius of the arcuate portion of the front member o of the clip is eccentric to the swing of said front member so that there obtains a perfect grip by simply pulling up 5 the bridge-piece q as far as it will conveniently go without straining, and the thumb-screw r whose point may engage in the one or the other of a series of indentations o^* in the arcuate face of the front 10 member o of the clip, serves partly as a handle means and partly as an adjusting means should different thicknesses of bedclothes or wear of spring necessitate adjustment.

15 Further, the top end t of the front clip member o is carried inwards beyond the opposing faces of the rubber pads p so as to push the bedclothes out of the perpendicular, thereby giving an increased grip on 20 said clothes by forming a kink in the same.

In many bedsteads fitted with wire springs or box springs, the hook-ended portion of the strap h is not absolutely necessary, the device being affixed to the bed rail d by 25 means of a hook-ended plate u extending perpendicularly from the back of the attachment plate a , as shown in Figure 3 of the drawings, a set-screw v in the hook end w of the extension plate u engaging under 30 the upper limb of the bed rail d , preventing swinging forward of the device, the mattress resting on the extension plate, the hook-ended portion of the strap being retained as an extra securing means should 35 such be necessary.

Further, a spring washer may be interposed between the head of the thumb-screw r and the bridge-piece q to maintain said thumb-screw tight, or, as shown in Figure 40 4, the thumb-screw r may be replaced by means of a spring-controlled plunger x .

I claim:—

1. Bedclothes retention means comprising a gripping member including an attachment 45 plate adapted to be detachably connected to the side rail of a bedstead, a guide member carried by the attachment plate, a spring-controlled slide bar slidably guided on said guide member, and resilient gripping jaws 50 carried by said spring-controlled slide bar.

2. Bedclothes retention means comprising one or more pairs of gripping members, each constituted by an attachment plate adapted 55 to be detachably affixed to the side rail of a bedstead in a vertical position in relation

thereto, a spring-controlled slide bar carried by and freely and vertically and slidably mounted in front of the attachment plate, a clip consisting of two rubber-faced jaw members hingedly connected together and fixedly connected by one member to said slide bar, and means pivotally carried by the fixed clip member to effect the instantaneous grip or the release of said grip.

3. Bedclothes retention means as claimed 65 by claim 2, characterized in that the attachment plate is detachably affixed to the bed rail by means of a buckled strap passed through slots in said attachment plate and around said bed rail, and to the wire mattress by means of a hook-ended strap affixed to said attachment plate, and that one arm 70 of the slide bar is slidable in a socket or sockets carried by the strap aforesaid and is connected by a spring to the lower end 75 of the attachment plate, and that the other arm of the slide bar has affixed thereto the inner member of the clip, and the outer member of the clip is of arcuate formation for the engagement therewith of the end of 80 a thumb-screw or equivalent device carried by a bridge-piece pivotally mounted on the lower end of the outer arm of the slide bar aforesaid.

4. Bedclothes retention means comprising 85 a gripping member including an attachment plate provided with a hook-ended plate extending perpendicularly from the back of said attachment plate for directly affixing said attachment plate to the bed rail, and means carried by the hook-end of said hook-ended plate to engage under the upper edge 90 of the bed rail, and means carried by said attachment plate for engaging the bedclothes.

5. Bedclothes retention means comprising 95 a gripping member including a member adapted to be detachably fixed to the side rail of a bedstead, a guide carried by said member, a bedclothes gripping member having a sliding engagement with said guide 100 and provided with resilient jaw members for engaging the bedclothes, and a spring anchored to said attachment plate and to said bedclothes gripping member for yieldingly pulling the same downwardly.

In testimony whereof I have affixed my signature hereto this 27th day of October 1926.

STEPHEN HENRY BARTTER.
